UNITED STATES PATENT OFFICE.

FRANK A. WEEKS, OF PLAINFIELD, NEW JERSEY.

INKSTAND.

1,325,821.

Specification of Letters Patent. Patented Dec. 23, 1919.

Application filed October 28, 1918. Serial No. 259,918.

To all whom it may concern:

Be it known that I, FRANK A. WEEKS, a citizen of the United States, and a resident of Plainfield, in the county of Union and 5 State of New Jersey, have invented certain new and useful Improvements in Inkstands, of which the following is a specification.

The invention relates more particularly 10 to a novel closure attachment for inkstands, this attachment embracing a disk to set within the mouth of the ink-well, automatically self-closing closure sections pivotally mounted on said disk and adapted to be 15 opened by an insertion of a pen between them and an upper annulus or ring having an open center and affording at its outer edges a shoulder adapted to rest upon a flange formed upon the base of the ink- 20 stand, said disk supporting the closure sections and being itself supported by said ring resting on said flange. Inkstands having hinged closure sections to be opened by passing a pen between them and being 25 self-closing are not new in this art, but the closure features in this class of inkstands have presented difficulties both from a manufacturing point of view and otherwise, and the purpose of my invention is to perfect to 30 a greater degree than has heretofore been done closure attachments for inkstands having self-closing closure sections.

The invention will be fully understood 35 from the detailed description hereinafter presented, reference being had to the accompanying drawings, in which:

Figure 1 is a top view of an inkstand constructed in accordance with and embodying the invention;

Fig. 2 is a vertical longitudinal section through the same, taken on the dotted line 2-2 of Fig. 1;

Fig. 3 is a vertical transverse section through the same taken on the dotted line 45 3-3 of Fig. 1;

Fig. 4 is an enlarged central section of the self-closing features of my invention detached from the inkstand, with the hinged cover or closure sections shown in their open 50 position by full lines and in their closed position by dotted lines, and

Fig. 5 is a top view of a portion of the same, the upper annular ring shown at the upper side of Fig. 4 being omitted from 55 Fig. 5.

In the drawings, 10 designates the glass

base or body of the inkstand, which base or body contains an ink-well 11 to receive ink 12 and comprises an annular flange 13 extending upwardly from the flat top 14 of 60 said base and surrounding the upper edges of the well 11. The flange 13 represents an upwardly projecting extension of a portion of the walls of the well 11 and serves to receive above the ink 12 the several features 65 constituting my invention and which will presently be referred to. The base 10 may be formed integrally with a pen rack 15.

The features constituting my invention comprise a disk 16, two corresponding cover 70 or closure sections 17 and an upper ring 18 which is in one piece and has an upper surface which is substantially semi-circular and a lower surface which is flat. The disk 16 is flat and of a diameter to enter within 75 the upper portion of the flange 13, as shown in Figs. 2 and 3, and said disk 16 is formed with a central opening 19 around whose upper edges there is an enlargement of said opening, as at 20, at the base of which enlargement is formed a horizontal annular shoulder 21. At the opposite sides of the upper portion of the opening 19, the disk 16 is formed with recesses 22 which extend 80 outwardly on horizontal lines from said opening 19 and afford seats for trunnions 23 which are integral with the closure or cover sections 17 and extend into said recesses.

The cover or closure sections 17 correspond with each other and are of hollow inverted cone outline when considered collectively and in their closed position, shown in Fig. 3, and said sections 17 are open and have along their upper outer edges a flange 95 24, the flanges 24 on both sections 17 defining substantially a ring, as shown in Fig. 5, adapted to seat upon the shoulder 21 of the disk 16, as shown in Fig. 3. The closure sections 17 are formed integrally with the trunnions 23, each of which is substantially semi-circular, as shown by the dotted lines in Fig. 4, and when in face to face relation, as shown by said dotted lines and by full lines in Fig. 5 form a substantially circular trunnion. The trunnions 23 have a bearing on 100 the bottoms of the recesses 22, and under the pressure of a pen applied downwardly between the sections 17 turn outwardly in a direction from each other, the lower facing surfaces of said trunnion 23 separating from 105 each other while their upper edges remain

110

2

together as will be understood on reference to Fig. 4. The trunnions 23 are substantially flush at their upper edges with the upper edges of the cover sections 17, and the flanges 5 24 on said cover sections when said sections are closed together are substantially flush with the upper surface of the disk 16.

The ring 18 extends from the inner edges of the enlargement 20 of the opening 19 outwardly beyond the outer edges of the disk 16, so that said ring 18 presents an opening 10 into which a pen may be passed and which permits the upward movement of the outer edges of the closure sections 17 when said sections are separated by a pen dipped into the ink-well. The overhanging outer edges of the ring 18 afford a shoulder which rests upon the flange 13 of the base 10, the outer edges of said ring 18 being flush with the 15 outer vertical surfaces of said flange so as to present a desirable finish to the inkstand. The disk 16 and ring 18 are secured together after the cover or closure sections 17 have been applied to position on the disk 16, and 20 the securing of the disk 16 and ring 18 together may be performed in various ways, but I preferably form studs 25 on the disk 16 and secure the same by cementing or otherwise in suitable recesses formed in the 25 base of the ring 18. The disk 16 supports the cover sections 17 and is itself supported by the ring 18 resting on the flange 13 of the base 10. The ring 18 confines the trunnions 23 to the recesses 22, and hence when all the 30 parts are assembled the closure may be handled as a unit and applied to and removed from the inkstand at will. The disk 16, closure sections 17 and ring 18 will preferably be molded from some suitable composition and the parts of the attachment constructed as hereinbefore described may be 35 readily assembled and will operate in an efficient manner. It is to be noted that the recesses 22 receive both trunnions 23.

40 45 The manner of utilizing the invention will be understood without special description. When the appliance is on the inkstand, a pen dipped downwardly between the closure sections 17 will cause said sections to open outwardly from each other in the manner shown in Fig. 4 by solid lines, and when the pen has been removed from the inkwell, the closure sections 17 will move together automatically to their closing position shown by solid lines in Fig. 3 and by dotted lines in Fig. 4. When the closure sections 17 are in their open position they bear against each other at the joint between the sections of the flanges 24 and the upper 50 edges of the pairs of trunnions 23, and when the closure sections 17 are in their closing position they bear against each other throughout their adjoining edges and the facing sides of the pairs of trunnions 23.

55 60 65 The studs 25 and the recesses which receive

the same in the ring member 18 serve to align the disk 16 and said ring member, and in addition to cementing said studs within said recesses the entire facing surfaces of the disk 16 and ring 18 may be cemented 70 together.

What I claim as my invention and desire to secure by Letters-Patent, is:

1. An inkstand comprising a base having an inkwell therein and a closure-appliance 75 for and over the top of said well comprising a disk closely fitting within the mouth of said well and having a central opening, matching converging cover-sections pivotally mounted on said disk and hanging 80 down through said central opening, and an upper ring-member secured to and upon said disk and suspending the same and at its outer edges resting freely upon the upper exposed surfaces of said base surrounding said well, said ring-member having a central dip opening of sufficient diameter to permit upper opposite side edge portions of said cover-sections to turn upwardly 85 into it when said sections are opened outwardly from each other at their lower portions.

2. An inkstand comprising a base having an inkwell therein and an upwardly projecting flange encompassing said well, and a 95 closure-appliance for and over the top of said well comprising a disk closely fitting within the mouth of said well and having a central opening, matching converging cover-sections pivotally mounted on said 100 disk and hanging down through said central opening, and an upper ring-member secured to and upon said disk and suspending the same and at its outer edges resting freely on the upper edges of said flange, said ring-member having a central dip opening coinciding with the opening in said disk and being of sufficient diameter to permit upper opposite side edge portions of said cover-sections to turn upwardly 105 into it when said sections are opened outwardly from each other at their lower portions.

3. An inkstand comprising a base having an inkwell therein and a closure-appliance for and over the top of said well comprising 115 a disk closely fitting within the mouth of said well and having a central opening, recesses at the sides thereof and an enlargement of said central opening around the upper edges thereof and forming at the base 120 of said enlargement an annular shoulder, matching converging depending cover-sections having trunnions pivotally supported in said recesses and upper outer edge flanges adapted to said shoulder, and an upper ring-member secured to and upon said disk and suspending the same and covering said recesses and trunnions and at its outer edges resting freely upon the upper exposed surfaces of said base surrounding said well, said 125 130

ring-member having a central dip-opening of sufficient diameter to permit upper opposite side edge portions of said cover-sections to turn upwardly into it when said sections 5 are opened outwardly from each other at their lower portions.

4. An inkstand comprising a base having an inkwell therein and a closure-appliance for and over the top of said well comprising 10 a disk fitting within the mouth of said well and having a central opening and recesses at opposite sides thereof, matching converging depending cover-sections having trunnions which match and engage each other within 15 said recesses and pivotally support said cover-sections, and an upper ring-member secured to and upon said disk and suspend-

ing the same and covering said recesses and trunnions and at its outer edges resting freely upon the upper exposed surfaces of 20 said base surrounding said well, said ring-member having a central dip-opening of sufficient diameter to permit upper opposite side edge portions of said cover-sections to turn upwardly into it when said sections 25 are opened outwardly from each other at their lower portions.

Signed at New York city, in the county of New York and State of New York, this 16th day of October, A. D. 1918.

FRANK A. WEEKS.
